Emil von Burg, New York, N. Y.

Application October 22, 1942, Serial No. 108,593

Term of patent 14 years

To all whom it may concern:

Be it known that I, Emil von Burg, a citizen of the United States, residing in the city of New York, county of New York, and State of New York, have invented a new, original, and ornamental Design for a Combination Wrist Watch and Compass and Strap Therefor, of which the following is a specification, reference being had to the accompanying drawing forming a part thereof.

Fig. 1 is a plan view of a combination wrist

watch and compass and strap therefor showing my design; and

Fig. 2 is a side view of the combination wrist watch and compass and strap therefor shown in Fig. 1.

I claim:

The ornamental design for a combination wrist watch and compass and strap therefor, as shown.

EMIL VON BURG.
